[57] CLAIM

The ornamental design for an incontinence electrode, as shown and described.

DESCRIPTION

FIG. 1 is a perspective view of an incontinence electrode showing our new design;

FIG. 2 is a side elevational view thereof, with all other sides being identical to that shown;

FIG. 3 is a top view thereof; and,

FIG. 4 is a bottom view thereof.

The broken line showing in FIGS. 1 and 2 is for illustrative purposes only and forms no part of the claimed design.
